UNITED STATES PATENT OFFICE.

JOSEPH ASHER, OF ALBANY, NEW YORK.

SASH-CORD-FASTENING DEVICE.

1,079,685.

Specification of Letters Patent. Patented Nov. 25, 1913.

Application filed October 8, 1912. Serial No. 724,645.

To all whom it may concern:

Be it known that I, JOSEPH ASHER, a citizen of the United States, residing at Albany, in the county of Albany and State of 5 New York, have invented certain new and useful Improvements in Sash-Cord-Fastening Devices, of which the following is a specification.

My invention relates to sash cord fasteners and has for its object to provide certain simple and inexpensive improvements in the connection between the sash cord, the fastening device and the sash, whereby the cord may be readily attached to and 10 detached from the fastening device without the raising or lowering of ears or projections and whereby the fastening device may be readily attached and detached from the sash without the use of a metal socket 15 device or the use of ears or projections but which sustains the weight without danger 20 of splitting or marring the sash and which can be readily and quickly detached from the sash whenever it becomes necessary or 25 desirable to remove it.

With these and other objects in view my invention consists in a combination of parts and arrangement of parts as will be hereinafter more fully described, shown in the 30 accompanying drawings and particularly pointed out in the appended claims, it being understood that changes in the proportion, size, material, metal and minor details may be made within the scope of the 35 claims without departing from the spirit or sacrificing any of the advantages of the invention.

Referring to the drawings, Figure 1 is a detail perspective view of the fastening device for application to the end of a sash cord, and shows the detail parts thereof. Fig. 2 is an elevation of a window sash equipped with a sash cord fastener embodying this invention. Fig. 3 is a central, longitudinal, sectional view showing one corner portion of a window sash, equipped with the sash cord fastening device and showing the manner of insertion of the sash cord to the fastening device. Fig. 4 is a 45 central, longitudinal sectional view of the fastening device. Fig. 5 is a detail and similar view of the fastening device showing the beveled or thickened edge of the circular head thereof.

Referring to the drawings, the letter W 55 designates the upper corner portion of a

window sash which is provided in its vertical edge with the usual cord groove G and circular groove, recess or seat R at the lower end of said groove, to receive the anchoring device for the cord.

The fastening device which is applied to the end of the sash cord consists of a laterally-bowed shank portion A which has one end, which is normally its lower end, 60 provided with an enlarged circular head B that lies in substantially the same plane with the shank and is connected thereto by means of a reduced neck portion, the opposite edges of the shank being bent so as to form a trough in which the cord C lies. The width of the shank is substantially the same as that of the reduced neck. The shank portion is provided with two rough 65 edged perforations D and E respectively, so 70 as to take in the cord C.

In carrying out the invention that portion of the shank lying between the perforations D and E, that is, F is pressed inward. It will be observed that in perforating the 75 shank at D and E it leaves the edge of the circular holes rough and by placing the cord C through D through the trough and then through E, F becomes a bridge or binder which keeps the cord from slipping from 80 the fastener and does away with the necessity of ears, projections and spurs. The edge of the circular head H is beveled thereby doing away with the necessity of a 85 metal socket to prevent its marring or splitting the sash. It will be further observed that the fastening device is inserted into the groove G and that the circular head is inserted into the socket R in such a manner 90 that the circular head rests against the foot 95 of the socket and that the cord C, as it passes beneath the bridge F, rests against the bottom of the groove G. The weight of the sash causes the top edge of B to press firmly against the top of the socket R and 100 holds B firmly in place without the necessity of spurs, projections or wings or fasteners of other kind. By this means the cord may be conveniently applied to and removed from the sash without damage to any 105 of the parts and does not require the removal of other fastening devices or the raising or clamping of ears, projections or spurs.

The advantage of the present form of sash 110 cord fastening device lies in the fact that the beveled edge of the circular head B does

away with the necessity of a metal lining to the socket recess or seat R to prevent the marring or splitting of the sash and that the circular head B being inserted deeply in the socket, recess R, and the strain of the weight of the sash falling upon the upper edge causing C to pull outward from the sash against said top of the circular head B causes the circular head B to remain in the socket R and the bowed shank A to remain in the groove G without the necessity of projections, spurs, or ears. Finally the fastening device may be struck from a blank of metal, then the shank bent into the form of a trough, the perforations D and E made, the bridge F bent into the form of an inverted shank thereby providing a strong, desirable and inexpensive form of sash cord fastening device.

20 What I claim as my invention and desire to secure by Letters Patent is—

1. In a device of the class described, a window sash, a groove in the vertical edge thereof, adapted to retain a cord, a recess at 25 the bottom of said groove being circular in form and wider and deeper than said groove, a shank adapted to fit in said groove, a head to said shank wider than said groove and adapted to fit deeply and in an inverse position in said recess, a portion of said shank bent upwardly forming a bridge, the shank and circular head adapted to be held in 30 place by the outward trend of the cord and the pressure of the upper part of the cir-

cular head against the upper walls of the 35 recess and adapted to hold the cord in place by the friction of the cord passing over the bridge, without projections, spurs or ears, a beveled edge to the circular head adapted to prevent the marring or splitting of the wood 40 of the sash.

2. In a device of the class described, a window sash having a groove in the vertical edge thereof, a recess in said sash at the bottom of said groove, wider and deeper than 45 said groove, a laterally bowed shank adapted to fit in said groove, the lower end of said shank forming a circular head, flat in form and broader than said groove and adapted to fit in said recess, a portion of said shank 50 bent upwardly forming a bridge, the said circular head adapted to be inserted deeply in said recess whereby the strain of the weight of the sash falls upon the upper edge 55 and causes the cord to pull outwardly from the sash against said top of the circular head causing the circular head to remain in the socket and the bowed shank to remain in the groove without the necessity of projections, spurs or ears, adapted to hold the 60 cord in place by the friction of the cord passing over the bridge.

In testimony whereof I do hereby affix my signature in presence of two witnesses.

JOSEPH ASHER.
